(57) **CLAIM**

I claim the ornamental design for a hanger, as shown and described.

DESCRIPTION

FIG. 1 is a perspective view of a hanger;

FIG. 2 is a top view of the hanger;

FIG. 3 is a bottom view of the hanger;

FIG. 4 is a front view of the hanger;

FIG. 5 is a right-side view of the hanger; and,

FIG. 6 is a left-side view of the hanger.

The broken lines shown represent unclaimed design and form no part of the claimed design.
